UNITED STATES PATENT OFFICE.

LILLIAN M. DUNN, OF CAMAS, WASHINGTON.

EXTENSION-TABLE.

1,265,067.

Specification of Letters Patent. Patented May 7, 1918.

Application filed December 2, 1916. Serial No. 134,765.

To all whom it may concern:

Be it known that I, LILLIAN M. DUNN, a citizen of the United States, residing at Camas, in the county of Clark and State 5 of Washington, have invented certain new and useful Improvements in Extension-Tables, of which the following is a specification.

This invention relates to tables, and particularly to extension tables. It provides a means for throwing the extra leaves into position when the table is extended. When the table is closed, the extra leaves are fitted under the top of the table out of the 15 way.

The object of the invention is to provide a convenient place for holding the extra leaves of the table.

A further object of the invention is to 20 provide an automatic means for throwing the leaves into position as the table is extended.

With these and other objects in view, the invention consists in the construction, combination and arrangement of parts as will be hereinafter fully described, illustrated in the accompanying drawing, and pointed out in the claim hereunto appended.

Figure 1 shows a side elevation of my invention.

Fig. 2 shows a bottom plan view.

Fig. 3 shows a sectional view on the line A—A Fig. 1.

Fig. 4 shows a sectional view on the line 35 B—B Fig. 2.

Fig. 5 shows a bottom plan view of one of the leaves.

Referring to the drawings like numerals designate like parts in the various drawings.

Numerical 6 indicates a table frame, having supporting legs 7, and the said frame 6 is transversely divided into two parts at its center. 8 is a top divided similarly to the frame 6. 9 is a rectangular frame slidably held inside the frame 6. 10 is a center strip running lengthwise between the ends of the frame 9. This strip 10 is wider at its upper side (see Fig. 3) than at its lower side.

11 indicate leaves, the center one being shown in raised position. These leaves have flat springs 12 secured at their centers to

the under side of the leaf, and their ends bent downwardly, so as to ride on the 55 frame 9. When the leaves are under the top 8, these springs 12 are pressed out and when the table is pulled out, the action of these springs will throw the leaf up to a level with the top 8. The center opening 60 in the top 8 and the leaves 11 have the usual pins in one side, and countersunk holes in the other side, for fitting them together. When desirous of closing the table it is necessary to pull it out slightly and press 65 down on the leaves which are desired to be taken out of the top part of the table. By pressing down the springs 12 will flatten out and allow the leaves to recede under the top 8.

Each leaf 11 has a pair of spaced blocks 70 13 which are adapted to lie on each side of the strip 10. The distance between these blocks 13 narrow as they extend out from the leaf, so that when the leaf is in a raised 75 position, these strips will tighten on the bevel side of the lengthwise strip 10, and thus limit the upward movement of the leaves 11.

The table has the usual cleats to support 80 the different parts, as are usually found in extension tables.

From the foregoing it is thought that the construction of my invention will be clearly understood, and therefore a more extended 85 explanation has been omitted.

What I claim as new, is,—

An extension table consisting of a frame mounted on suitable legs, a top mounted on said frame, a second frame slidably mounted 90 in said first frame, a V-shape strip centrally positioned lengthwise in said second frame, leaves adapted to be carried on said second frame, leaf springs carried under said leaves and adapted to adjust said 95 leaves in position to form a section of said top when desired, and said V-shaped strip limiting the upward movement of said leaves.

In testimony whereof I affix my signature 100 in the presence of two witnesses.

MRS. L. M. DUNN.

Witnesses:

T. S. WOOLSON,
JOHN DUNN.
